144,465

DESIGN FOR A TEXTILE FABRIC OR SIMILAR ARTICLE

Sidney Meyer, New York, N. Y.

Application July 25, 1945, Serial No. 120,953

Term of patent 7 years

(Cl. D92—1)

To all whom it may concern:

Be it known that I, Sidney Meyer, a citizen of the United States, residing at New York, in the county of New York and State of New York, have invented a new, original, and ornamental Design for a Textile Fabric or Similar Article, of which the following is a specification, reference being had to the accompanying drawing, forming part thereof.

The figure is a plan view of a portion of a textile fabric showing my new design. The design unit is contained between the dot and dash lines, which unit is repeated in regular succession as indicated by the extensions beyond the unit boundaries.

I claim:

The ornamental design for a textile fabric or similar article, substantially as shown and described.

SIDNEY MEYER.
